UNITED STATES PATENT OFFICE.

CHARLES E. SARGENT, OF CHICAGO, ILLINOIS.

ENGINE-STARTING DEVICE.

1,162,193.

Specification of Letters Patent. Patented Nov. 30, 1915.

Application filed June 19, 1911. Serial No. 634,040.

To all whom it may concern:

Be it known that I, CHARLES E. SARGENT, citizen of the United States, residing at Chicago, in the county of Cook and State 5 of Illinois, have invented certain new and useful Improvements in Engine-Starting Devices, of which the following is a specification, reference being had therein to the accompanying drawing.

10 My invention relates to starting internal combustion engines by means of compressed elastic fluid and the principal object is to provide very simple devices whereby the engine may be started by simply opening an 15 ordinary valve which may be closed if desired after the engine has begun to act as an explosion engine, or may be left open to supplement the power derived from the explosions when the engine is overloaded, the 20 fluid under pressure being automatically cut off when it is not needed.

In the accompanying drawings, Figure 1 is a side elevation, partly in section, showing a portion of a horizontal engine with my devices in position thereon. Fig. 2 shows in 25 axial section a portion of a vertical engine provided with a modified embodiment of the same invention. Fig. 3 is a section on the line 3—3, Fig. 2. Fig. 4 is a section on 30 the line 4—4, Fig. 3.

In Fig. 1, A represents the cylinder of a horizontal engine, B the usual side or cam shaft, C a cam thereon, D a pivoted bell-crank lever carrying at its outer end a roller 35 E to meet the cam and at its other end pivotally connected to an outwardly open hollow plunger F which contains a helical spring G and works in a small cylinder H communicating through a passage I with the 40 interior of the engine cylinder A. The plunger is provided with a shoulder or offset F' which, when the plunger moves inward, meets the outer end of the small cylinder or other stop limiting the movement. At its 45 inner end, the plunger preferably bears an axial extension F² which is axially bored to form a sliding bearing for the stem J of a valve J' for closing the passage I. The stem extends axially through the spring and 50 at a point beyond the plunger bears a collar J² resting against the outer end of the spring and adjusted in position by means of nuts J³. The collar limits the outward movement 55 of the plunger, which when moved outward against the collar holds the valve firmly

closed. A passage K, controlled by a valve K', serves for admitting elastic fluid under pressure, from a reservoir or other source of supply, to the cylinder H whenever it may be desired. Whenever the valve K' is closed, 60 the starting devices are out of commission, the spring holding the valve J' closed and the roller E slightly outside the path of the cam, and the spring being strong enough to resist the slight suction tending to open 65 the valve J' during the admission of a combustible charge to the engine cylinder, the engine may act indefinitely as if no starting devices were provided.

When the valve K' is opened, the elastic 70 fluid under pressure enters the cylinder H and forces the plunger slightly outward until the roller rests upon the high portion of the cam and also opens the valve J', by overcoming the resistance of the spring, so 75 that the compressed fluid enters the engine cylinder and forces the piston therein to move as in a working stroke. This movement causes the side shaft and cam to rotate, whereby, at the end of the power stroke, the 80 high portion of the cam moves from roller supporting position and since the area of the working face of the plunger F exceeds that of the valve J', and the cam now offers no resistance, the plunger is immediately 85 forced outward against the collar upon the valve stem, thus closing the valve J' and holding it closed, ordinarily, until the roller is again pushed outward by the cam, provided that the valve K' be not closed mean- 90 time. I prefer to have the pressure of the elastic fluid slightly exceed that of the compressed explosive charge, but it is obvious that this fluid will not enter the engine cylinder unless the pressure in the engine cylinder plus the tension of the spring falls below the pressure in the small cylinder. If the compressed mixture is not ignited when the valve J' is allowed to open, compressed 95 fluid will flow into the cylinder until the 100 roller leaves the cam, just as is the case in starting.

Whether the starting valve is in commis- 105 sion or not, the engine, when in operation, will draw in combustible mixture, and com- press and explode it just at the time the starting valve should open; therefore if the igniter fails or the mixture is not combustible, or if for any cause the pressure within the cylinder drops below the pressure of the 110

starting fluid, the valve J' will open and allow the compressed fluid to flow into the cylinder.

When the cylinder is working normally by explosive impulses, the pressure within it will be higher than the pressure of the starting fluid for about $\frac{1}{4}$ of the working stroke, and therefore if the valve K' is left open, the engine will run on the pressure generated by the explosive mixture and the pressure of the starting fluid, but as the starting fluid is compressed by the engine, there is no advantage in keeping the valve K' open after the engine is up to speed. If, however, the engine during light loads be permitted to store fluid under pressure, the store of fluid can be used to increase the power of the engine later when the latter is loaded beyond its normal capacity by simply opening or leaving open the valve K' , thereby returning to the engine some of the power which it has stored while under light load. Usually, then, as soon as the engine is working under its own impulses, the valve K' is closed, and the starting devices cease to act, the roller being outside the path of the cam, and the spring holding the valve J' closed indefinitely.

In Figs. 2, 3, 4, A' represents the cylinder of a vertical engine, A^2 the power shaft, A^3 the inlet valve, A^4 the exhaust valve, both valves being operated by cam devices X , without novelty, supported upon a fixed stud Y and actuated from the power shaft by means of gears Z . H' is a small cylinder in which works a hollow plunger F^3 provided with a forked stem F^4 bearing at its lower end a roller E' , in the plane of a cam C' driven by the gears Z , and normally slightly outside the cam's path. The plunger contains a spring coil G^2 which presses against a collar J^4 adjustably fixed upon the stem J^5 of a valve J^6 controlling a passage from the small cylinder into the engine cylinder. Elastic fluid under pressure is admitted to the small cylinder through a conduit K^2 , controlled as before by a valve (not shown). The compressed fluid being admitted to the small cylinder, the plunger therein is forced slightly down so that the roller meets the higher portion of its cam and the valve J^6 is forced open, the spring yielding, and the fluid enters the engine cylinder. When by the movement of the engine piston the cam is rotated so far that the roller is not supported, the excess of pressure upon the plunger moves it outward and thus closes the valve J^6 . So long as the fluid under pressure is not cut off, the engine works as in the case first described, the action and advantages being similar, and when the compressed fluid is cut off the roller rises from the path of the cam and the whole device is out of commission. It is obvious that with either form, explosive gas being cut off from

the engine, the engine may work as a simple compressed fluid motor instead of acting as an internal combustion engine, and also that the same devices may be applied, with certain additional advantages, to all the explosion cylinders of multiple cylinder engines. In practice, it has usually been applied to four cycle engines, but it is not limited to that type.

What I claim is:

1. The combination with an engine cylinder provided with a compressed fluid conduit leading into the cylinder, of an admission valve governing the passing of fluid into the cylinder and arranged to receive both opening pressure and closing pressure from the fluid in the conduit, a spring resisting the opening of the valve with a force less than said opening pressure, and an engine actuated member arranged to move periodically into and out of position for receiving said closing pressure and relieving the valve therefrom, whereby the opening pressure overcomes the force of the spring and opens said valve.

2. In apparatus of the class described, the combination with an engine cylinder provided with a conduit for admitting compressed fluid thereto, of operator-actuated means for controlling the flow of compressed fluid into said conduit, a valve controlling the passage of fluid from said conduit to the cylinder, a plunger arranged for moving, under the pressure of fluid in said conduit, to position for resisting the opening of the valve by the pressure of the fluid, and automatically operating means for periodically moving the plunger from such resisting position.

3. The combination with an internal combustion engine provided with a port for admitting fluid under pressure, a small cylinder alining with said port and communicating therewith, a plunger working in said cylinder, a valve controlling said port and having a stem extending through said plunger and provided with a stop beyond its bearing in the plunger, a spring interposed between said stop and plunger, an engine actuated cam, and means whereby the cam in its rotation resists outward movement of the plunger at points varying with its own position, and valve controlled means for admitting compressed fluid to said cylinder.

4. The combination with an internal combustion engine provided with a port for admitting compressed fluid, of a small cylinder alining and communicating with said port, a plunger working in said cylinder, a stop limiting the inward movement of the plunger, a valve, for closing said port, provided with a stem having a sliding bearing in said plunger and a plunger-engaging stop beyond the latter, a spring interposed between the plunger and the stop last men-

tioned, an engine rotated cam, a roller in the plane of the cam and normally outside its path, means whereby slight outward movement of the plunger moves the roller to said path, and hand operated means for admitting compressed fluid to said cylinder.

5. The combination with an engine cylinder, of a compressed fluid chamber communicating with the cylinder through a port, a valve for said port, a piston arranged in the chamber for outward movement limited by the valve, hand controlled means for admitting compressed fluid between the valves and piston, and engine operated means, arranged to be brought into action by the outward movement of the piston, for forcing the latter inward at intervals, whereby it becomes an abutment for valve-opening air pressure.

20 6. The combination with an engine cylin-

der having an admission port and a valve controlling the same, of a compressed fluid chamber communicating with said port, a piston, in said chamber, and adapted to engage, at the outer limit of its path, the valve and resist its opening, hand controlled means for admitting compressed fluid to said chamber between said port and piston whereby the piston is moved outward into engagement with the valve, and engine-operated means for periodically forcing the piston inward to free the valve and serve as an abutment for valve opening pressure of the fluid.

In testimony whereof I affix my signature 35 in presence of two witnesses.

CHARLES E. SARGENT.
